US00D554381S

(12) **United States Design Patent** (10) **Patent No.:** **US D554,381 S**
Valdiserri et al. (45) **Date of Patent:** **** Nov. 6, 2007**

(54) **SEATING UNIT**

(75) Inventors: **David G. Valdiserri**, Grand Rapids, MI (US); **Gardner J. Klaasen, II**, Ada, MI (US); **Kirt D. Martin**, Alto, MI (US); **David C. Eberlein**, Hudsonville, MI (US)

(73) Assignee: **Steelcase Development Corporation**, Caledonia, MI (US)

(**) Term: **14 Years**

(21) Appl. No.: **29/231,566**

(22) Filed: **Jun. 7, 2005**

(51) **LOC (8) Cl.** **06-01**

(52) **U.S. Cl.** **D6/366**

(58) **Field of Classification Search** D6/374, D6/375, 334-336, 366, 377, 379-380, 500-502; 297/452.21, 452.26, 452.29, 452.35, 452.32, 297/452.48, 411.2, 411.27, 411.24

(57) **CLAIM**

We claim the ornamental design for seating unit, as shown.

DESCRIPTION

FIG. 1 is a perspective view of a second seating unit embodying the present invention;

FIG. 2 is a front view of the seating unit shown in FIG. 1; FIG. 3 is a right side view of the seating unit shown in FIG. 1, the left side being a mirror image thereof;

FIG. 4 is a rear view of the seating unit shown in FIG. 1; FIG. 5 is a top view of the seating unit shown in FIG. 1; and, FIG. 6 is a bottom view of the seating unit shown in FIG. 1. The broken lines are for illustrative purposes only and form no part of the claimed design.

1 Claim, 3 Drawing Sheets
